UNITED STATES PATENT OFFICE

GEORGE P. MARSHALL, OF WASHINGTON, DISTRICT OF COLUMBIA

DESIGN FOR A STORE

Application filed November 2, 1929. Serial No. 33,270. Term of patent 3½ years.

To all whom it may concern:

Be it known that I, GEORGE P. MARSHALL, residing at Washington, in the District of Columbia, have invented a new, original, and ornamental Design for a Store, of which the following is a specification, reference being had to the accompanying drawing, forming part thereof.

Fig. 1 is an elevational view of a conventional front of a store, and

Fig. 2 is a perspective view of the interior of a store showing my new design.

The dominant feature of my design consists of the interior ornamentation as presented in Fig. 2.

I claim:

The ornamental design for a store as shown.

GEORGE P. MARSHALL.
